(57) CLAIM

The ornamental design for the hair clipper, as shown and described in the accompanying figures.

DESCRIPTION

FIG. 1 is a perspective view of a hair clipper according to the present invention;

FIG. 2 is a top view of the hair clipper of FIG. 1;

FIG. 3 is a front elevational view of the hair clipper of FIG. 1;

FIG. 4 is a right side elevational view of the hair clipper of FIG. 1;

FIG. 5 is a left side elevational view of FIG. 1;

FIG. 6 is a rear elevational view of the hair clipper of FIG. 1; and,

FIG. 7 is a bottom view of the hair clipper of FIG. 1.

The portions shown in broken lines are for illustrative purposes only and forms no part of the claimed design.
